UNITED STATES PATENT OFFICE.

EDGAR H. JOHNSON, OF NEW YORK, N. Y., ASSIGNOR OF ONE-HALF TO THE FARREL FOUNDRY AND MACHINE COMPANY, OF ANSONIA, CONNECTICUT.

MACHINE FOR MAKING CABLE.

SPECIFICATION forming part of Letters Patent No. 624,817, dated May 9, 1899.

Application filed June 14, 1898. Serial No. 683,409. (No model.)

To all whom it may concern:

Be it known that I, EDGAR H. JOHNSON, a citizen of the United States, residing at New York, (Brooklyn,) county of Kings, State of New York, have invented a new and useful 5 Machine for Making Cables, of which the following is a specification.

My invention relates to cabling-machines generally—that is, machines for twisting strands into a cable or for covering a core with one or more layers of strands; and the special object in view is to provide a comparatively simple and inexpensive machine which shall be compact in arrangement, so 15 as to greatly decrease the amount of space required, in which the spool-frames shall be set obliquely to the axis of the rotating head, and in which the spool-frames as they are carried about by the rotating head will maintain a 20 uniformly horizontal position—that is to say, an independent axial movement is imparted to each spool-frame which just neutralizes the effect on the frames of the axial movement of the head.

With these ends in view I have devised the novel machine for making cables of which the following description, in connection with the accompanying drawings, is a specification, letters and numbers being used to designate the several parts.

Figure 1 is a plan view of the machine complete, the spools and spool-frames appearing in operative position, the spools for the sake of clearness being shown as empty and the outer portion of the fifth web-wheel in section; Fig. 2, a side elevation of the frame and the mandrel and web-wheels of the rotating head, the spool-frames and gearing being omitted, but the position of the spools being indicated by dotted lines; Fig. 3, a plan view, partly in section and on an enlarged scale, of the rotating head, the outer rows only of spool-frames and spools being shown; Fig. 4, a cross-section of the hollow mandrel on the line $x-x$ in Fig. 3, one of the web-wheels appearing in elevation and the position of the spools being indicated by dotted lines; Fig. 5, a section on the line $y-y$ in Figs. 2 and 3; Fig. 6, a detail view showing the reverse side 50 from that which appears in Fig. 4 of one of the

gear-wheels carried by all except the first and the last of the web-wheels; Fig. 7, a sectional view, on an enlarged scale, on the line $z-z$ in Figs. 1 and 2, illustrating mechanism for changing the speed of the drawing-drum; Fig. 8, a detail view, on an enlarged scale, showing the mode in which the strands are twisted, the beveled end of the hollow mandrel being shown in elevation and the die in section; and Fig. 9 is an enlarged detail view 60 corresponding with Fig. 3, showing another mode in which motion may be communicated to the shaft which imparts axial movement to the spool-frames.

A denotes the bed of the machine, which is 65 supported by legs B; C, a hollow mandrel journaled in boxes F on standards D, which extend above the bed, and E web-wheels, whose hubs 2 are rigidly secured to the hollow mandrel in any suitable manner, as by set-screws 70 3. These web-wheels and the parts carried thereby and the hollow mandrel are collectively termed the "rotating head." In the present instance the boxes in which the mandrel is journaled are shown as provided with 75 antifriction-rollers 4, made hollow for the sake of lightness, which surround the mandrel. Upon the outer face of the first web-wheel E and rigidly secured thereto is a gear-wheel 5. In the present instance I have 80 shown this gear-wheel as supported by a circular flange 6 on the web-wheel and as secured to the web-wheel by bolts 7. Motion is imparted to the rotating head by means of a pinion 8, which meshes with gear-wheel 5. 85 This pinion is carried by a shaft 9, which is provided with fast and loose pulleys 10 and 11, over which a belt (not shown) passes.

G denotes the spool-frames, and H the spools therein. These spool-frames are so shaped, 90 the forward ends converging, as to permit them to be mounted obliquely to the axis of the rotating head. The rear or upper ends of the spool-frames are provided with journals 12, having their bearings in oblique hubs 13, which are provided with flanges 14, by which they are riveted or otherwise secured to the peripheries of the web-wheels. The forward or lower ends of the spool-frames are provided with journals 15, which have their 95 100

bearings in oblique hubs 16 upon the web-wheels, the respective ends of each set of spool-frames being journaled on different web-wheels. Journals 15 and hubs 16 are 5 provided with holes 17, through which the strands (wire or thread) from the spools pass. Hubs 16 also carry bevel-pinions 18, which mesh with bevel gear-teeth 19 on wheels I, mounted to turn on flanges 20 upon the web- 10 wheels. The gear-wheels I are provided with flanges 21, and said wheels are retained in position on flanges 20 by means of overhanging rings 22, which are bolted to the web-wheels, so as to retain wheels I in position thereon, 15 but at the same time to permit free rotary movement of the gear-wheels independently of the web-wheels.

23 denotes internal gear-teeth on wheels I, which are engaged by pinions 24, carried by 20 a shaft 25, which is itself journaled in hubs 26 on the web-wheels. (See Fig. 4 in connection with Fig. 3.) It is by means of the pinions 24 on shaft 25 that the axial movement is imparted to the spool-frames, which neutralizes the axial movement of the head and 25 retains the spool-frames at all times in a horizontal position. Rotary movement may be imparted to shaft 25 either in the mode illustrated in Fig. 3 or in the mode illustrated in 30 Fig. 9. In Fig. 3 I have shown a web 27 rigidly secured to the box F at the rear end of the rotating head, said web being provided with internal gear-teeth 28. (See Fig. 5 in connection with Fig. 3.)

35 29 denotes an idler-pinion carried by a stud 30, fixed in the first web-wheel and meshing with internal gear-teeth 28, and also with a pinion 31 on shaft 25, as clearly shown in Figs. 3 and 5.

40 In Fig. 9 I have illustrated a modified form of mechanism for imparting rotation to the pinion-shaft. Instead of a web 27 provided with internal gear-teeth I attach to the box F at the left end of the machine, as seen in 45 the drawings, a web 44 provided with external gear-teeth 45, which mesh directly with pinion 31 on shaft 25, thereby doing away with the idler-pinion 29.

Any convenient number of sets of spool- 50 frames may be used and any convenient number of spool-frames in each set. By lengthening the frame and mandrel the number of web-wheels, and consequently the number of spool-frames and spools, may be increased indefinitely. In the present instance I have shown ten spool-frames in each set and four sets of spool-frames and spools requiring five web-wheels, the first web-wheel—that is, the one appearing at the left in Fig. 3 and the one to 55 which power is applied—not being provided with hubs 16. The third, fourth, and fifth web-wheels (see Fig. 4 and dotted lines in Fig. 3) are provided with holes 32, through which the strands pass. The forward end of the low 60 mandrel extends through and beyond the standard D, appearing at the right in Figs. 65

1 and 2, the extreme forward end of said mandrel being beveled, as at 33. (See Fig. 8.)

34 denotes a die supported by arms 35, extending forward from the standard upon 70 which the forward end of the hollow mandrel is journaled. This die condenses the strands, and owing to the rotary movement of the head wraps or twists them about a core or about each other, as clearly shown in Fig. 8. 75

The cable is drawn through the machine by means of a drawing-drum J, journaled in boxes K at the forward end of the bed. The cable is passed several times about this drum, so as to take firm hold thereon, and thence 80 passes to a winding-drum. (Not shown in the drawings.) Upon the side of the drawing-drum is a bevel gear-wheel 36, which is engaged by a bevel-pinion 37 on a shaft 38. (See Fig. 1.) Motion is imparted to shaft 38 85 and through said shaft to the winding-drum by means of a gear-wheel 39, meshing in the present instance with an idler-pinion 40, which in turn meshes with a gear-wheel 41 on a shaft 42. At the other end of shaft 42 90 is a gear-wheel 43, which meshes with a gear-wheel in a speed-changing device, which as a whole I have designated by L. This speed-changing device appears in Figs. 1 and 2 and on a larger scale in Fig. 7. I do not care to 95 describe it in detail, however, as specifically it forms no portion of my present invention. It is sufficient for the purposes of this specification to say that any speed-changing device may be used to control the speed of the 100 drawing-drum, it being obvious that the slower the speed of the drawing-drum the closer or shorter will be the twist of the strands, and that as the speed of the drawing-drum is increased, the speed of the rotating head being at all times the same, the longer will be the twist of the strands—that is to say, the strands will lie more nearly parallel to the axis of the cable itself. Gear-wheel 39 is of course provided with holes 105 through which the strands pass. These holes do not appear in the drawings, but are similar to the holes 32 in the web-wheels, which are shown in Fig. 4 and are indicated by dotted lines in Fig. 3.

115 The operation is as follows: If a core is to be covered, the core is passed through the hollow mandrel and through the die and the strands are wrapped about it at the die in precisely the same manner that they are twisted 120 together in Fig. 8, the only difference being that where a core is used the strands are twisted about the core and where no core is used, as in Fig. 8, the strands are simply twisted together. In threading the machine 125 the operator places as many spools in the spool-frames of each set as may be required and makes use of as many sets of the frames as may be required, it being of course wholly immaterial whether all the sets of spool-frames are in use or whether all the frames 130 in each set carry spools. The operator passes

the strands from the spools in the first set through the holes 17 in the journals 15 and hubs 16 upon the second web-wheel, then through the holes 32 in the third web-wheel, 5 and so on, the holes 32 in the fourth web-wheel receiving strands from the first and second sets of spools, the holes 32 in the fifth web-wheel receiving the strands from the first, second, and third sets of spools, 10 and the holes (not shown) in gear-wheel 39 receiving the strands from all the sets of spools, it being of course understood that the third, fourth, and fifth web-wheels and the gear-wheel 39 contain a number of holes corresponding in number to the largest number 15 of spool-frames and spools that can be used in each set. The strand from each spool passes through the special hole 17 corresponding thereto; but each set of holes 32 receives 20 the strands from all the spools lying back of said hole and the holes in gear-wheel 39 receive the strands from all the spools. It should be understood that the core when used is not rotated, but that the head, which consists of the hollow mandrel, the web-wheels, 25 and the spool-frames and spools carried thereby, rotates continuously in use. Although the head is constantly in rotation, there is no twisting of the strands until they are condensed at the die. This result is accomplished by means of shaft 25, which is journaled in the web-wheels and carried about by them and to which a rotary movement is imparted wholly independent of the rotation of 30 the web-wheels and gearing intermediate said shaft and the spool-frames, the action of which is to impart an axial movement to the spool-frames, which just neutralizes the effect on the spool-frames of the axial movement of 35 the head. In other words, while the spool-frames are carried about by the head in its rotation they receive through the mechanism just referred to an independent axial movement in the opposite direction from the rotation of the head, the result of this compound movement being to retain the spool-frames and spools in a horizontal position at all times as they are carried about by the head and 40 without any twisting whatever of the strands 45 themselves until they are condensed and twisted at the die. It will be noted that as the spool-frames receive their axial movement from the head itself perfect timing of the action of the spool-frames is insured at 50 all times, no matter whether the head may be running fast or slow. As already stated, the closeness of the twist of the strands depends upon the speed with which the completed cable is drawn from the machine by the drawing-drum. By that I mean the speed of the drawing-drum relative to the speed of the 55 rotating head. If a less amount of twist is required in the strands—that is, if it is required to have the strands lie more nearly parallel to the axis of the cable—the relative

speed of the drawing-drum is increased. If it is desired to give a closer twist to the cable—that is, have the strands lie more oblique to the axis of the cable—the relative speed of the drawing-drum is lessened, it being contemplated that the speed of the rotating head shall be uniform at all times and that the desired changes in the twist of the cable shall be effected through a suitable speed-changing device which controls the speed of the drawing-drum. 75

Having thus described my invention, I claim—

1. In a machine of the character described, the combination with a fixed die through which the strands pass of a central rotating mandrel provided with a series of web-wheels each having a circular series of spool-frames, a gear-wheel mounted on each of said web-wheels, a shaft provided with pinions meshing with said gear-wheels for giving an independent movement to said gear-wheels, and connections between said gear-wheels and spool-frames whereby said spool-frames are given an axial movement in the opposite direction from the web-wheels, the effect of which is to maintain the spool-frames at all times in a horizontal position. 80

2. In a machine of the character described, the combination with a mandrel and web-wheels carried thereby, said web-wheels with the exception of the last having hubs 13 near their peripheries and with the exception of the first having hubs 16 between their peripheries and the mandrel and much nearer the mandrel than the hubs 13, of obliquely-arranged spool-frames the outer ends of which are journaled in hubs 13 and the inner ends of which are journaled in hubs 16 on the next web-wheels, a single continuous shaft carried 95 by said web-wheels, means for rotating said shaft independently of said web-wheels, and connections between said shaft and said spool-frames whereby the latter are maintained in a horizontal position at all times. 100

3. In a machine of the character described, the combination with a mandrel and web-wheels carried thereby, said web-wheels with the exception of the last having hubs 13 near their peripheries and with the exception of the first having hubs 16 between their peripheries and the mandrel and much nearer the mandrel than the hubs 13, of obliquely-arranged spool-frames the outer ends of which are journaled in hubs 13 and the inner ends 110 of which are provided with journals bearing in hubs 16, said journals and said hubs 16 having holes 17 through which strands may pass, a gear-wheel carried by each of said web-wheels but movable independently of said web-wheels, pinions supported by said web-wheels for driving said gear-wheels, means for rotating said pinions independently of said web-wheels, in a direction opposite to the direction of rotation of said web-wheels, and 115

120

125

130

connections between said gear-wheel and said spool-frames, whereby the latter are maintained in a horizontal position at all times.

4. The combination with the mandrel, and the web-wheels having flanges 20, hubs 26, shaft 25 journaled in said hubs and carrying pinions 24, and spool-frames journaled on the web-wheels and provided with bevel-pinions 18, of wheels I having internal gear-teeth 23 10 which are engaged by the pinions 24 and bevel gear-teeth 19 which mesh with bevel-pinions 18 and means for imparting rotation to shaft 25 whereby axial movement is imparted to the spool-frames in the opposite direction from the rotation of the web-wheels.

5. The combination with the mandrel provided with web-wheels, and spool-frames journaled on the said web-wheels obliquely to the said mandrel, of mechanism for imparting 20 rotary movement to the mandrel and web-wheels and a continuous shaft carried by said web-wheels but movable independently thereof and a series of pinions carried by said shaft for imparting rotary movement in the 25 opposite direction to the spool-frames, substantially as described for the purpose specified.

6. The combination with the mandrel, the web-wheels and spool-frames journaled on 30 the web-wheels obliquely to the mandrel, and provided with bevel-pinions 18, of wheels I having bevel gear-teeth 19 meshing with the bevel-pinions and internal gear-teeth 23, shaft 25 having pinions 24 meshing with the internal gear-teeth, and means for rotating said mandrel and shaft 25.

7. The combination with the mandrel, the web-wheels having flanges 20 and spool-frames journaled on the web-wheels obliquely 40 to the mandrel and provided with bevel-pinions 18, of wheels I mounted to turn on flanges 20 and provided with flanges 21 and bevel gear-teeth 19 meshing with the bevel-pinions, rings 22 by which wheels I are loosely 45 retained in position and means for imparting rotary movement to said wheels in the opposite direction from the rotation of the mandrel.

8. The combination with the mandrel, the 50 web-wheels having flanges 20 and hubs 26 and spool-frames journaled on the web-wheels and provided with bevel-pinions 18, of wheels I mounted to turn on flanges 20 and having flanges 21, internal gear-teeth 23 and bevel 55 gear-teeth 19 meshing with the bevel-pinions, rings 22 by which wheels I are loosely re-

tained in position and shaft 25 journaled in hubs 26 and carrying pinions engaging internal gear-teeth on wheels I.

9. The combination with the mandrel, the 60 web-wheels having holes 32 and oblique hubs 13 and 16, said hubs 13 being near the peripheries of the said web-wheels and the said hubs 16 being relatively near the said mandrel, and spool-frames journaled in said hubs 65 70 and carrying spools, the journals which bear in hubs 16 and said hubs themselves having holes 17, of mechanism for imparting rotary movement to the mandrel and web-wheels and mechanism consisting of a single continuous shaft carried by the web-wheels but rotating independently thereof for imparting rotary movement in the opposite direction to the spool-frame, strands from the said spools passing out through holes 17 and 32. 75

10. The combination with the mandrel journaled in boxes F, the web-wheels and spool-frames journaled on the web-wheels obliquely to the mandrel, of gear-wheel 5 upon the outer face of the first web-wheel through 80 which motion is imparted to the mandrel and web-wheels, shaft 25 journaled in the web-wheels and carrying a pinion 31, web 27 secured to one of the boxes and having internal gear-teeth 28, an idler-pinion 29 carried by 85 the first web-wheel and lying between the internal gear-teeth and pinion 31 and mechanism, substantially as described and shown, between shaft 25 and the spool-frames which rotates the spool-frames in the opposite direction from the mandrel.

11. The combination with the drawing-drum and the die, of a rotating mandrel, web-wheels carried thereby and each carrying a circular series of spool-frames journaled on 90 the web-wheels obliquely to the mandrel, gear-wheels on said spool-frames, a continuous shaft carried by said web-wheels and provided with pinions for rotating the spool-frames in the opposite direction from the 100 mandrel, and a speed-changing device intermediate the mandrel and the drawing-drum whereby the speed of the latter may be changed in use to regulate the twist of a cable.

In testimony whereof I affix my signature in presence of two witnesses.

EDGAR H. JOHNSON.
